CLAIM

The ornamental design for a stand for audio player, as shown and described.

DESCRIPTION

FIG. 1 is a front, right side, perspective view of a stand for audio player showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of the stand for audio player shown in an environment of use.

The broken lines shown in the drawings depict environment structure that forms no part of the claimed design.

1 Claim, 8 Drawing Sheets
